CLAIM

The ornamental design for a multi-element jewelry, as shown and described.

DESCRIPTION

FIG. 1 is a front perspective view of the first jewelry element showing my new design;

FIG. 2 is a front elevation view thereof;

FIG. 3 is rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a front perspective view of the second jewelry element showing my new design;

FIG. 9 is a front elevation view thereof;

FIG. 10 is rear elevation view thereof;

FIG. 11 is a left side elevation view thereof;

FIG. 12 is right side elevation view thereof;

FIG. 13 is a top plan view thereof;

FIG. 14 is a bottom plan view thereof;

FIG. 15 is a front perspective view of the third jewelry element showing my new design;

FIG. 16 is a front elevation view thereof, the rear elevation view being a mirror image thereof;

FIG. 17 is a left side elevation view thereof, the right side elevation view being a mirror image thereof;

FIG. 18 is a top plan view thereof;

FIG. 19 is a bottom plan view thereof;

FIG. 20 is a front perspective view of the fourth jewelry element showing my new design;

FIG. 21 is a front elevation view thereof, the rear elevation view being a mirror image thereof;

FIG. 22 is a left side elevation view thereof, the right side elevation view being a mirror image thereof;

FIG. 23 is a top plan view thereof;

FIG. 24 is a bottom plan view thereof; and,

FIG. 25 is a front perspective view of the multi-element jewelry showing my new design.

(Continued)

The broken lines shown in the drawings illustrate portions of the multi-element jewelry that form no part of the claimed design.
